UNITED STATES PATENT OFFICE.

THOMAS JEROME COE, OF BROOKLYN, NEW YORK.

EXHIBITOR.

1,168,786.

Specification of Letters Patent.

Patented Jan. 18, 1916.

Application filed June 1, 1912, Serial No. 709,968. Renewed August 9, 1915. Serial No. 44,609.

To all whom it may concern:

Be it known that I, THOMAS JEROME COE, a citizen of the United States, and resident of Greenpoint, Brooklyn, in the county of 5 Kings and State of New York, have invented certain new and useful Improvements in Exhibitors, of which the following is a specification.

This invention relates to devices adapted 10 for the exhibition of signs and advertising matter of various descriptions.

One object of the invention is to produce a simple and efficient device for the purpose stated, which admits of being manufactured 15 at low cost.

A further object is the production of an exhibitor wherein the sign displaying member can be quickly and conveniently changed.

Another object is to provide an improved 20 actuating mechanism for the exhibitor, capable of driving additional sign-carrying members.

With these objects in view, the invention 25 consists in the improvements and combinations of parts hereinafter described and pointed out in the appended claims.

In the drawings illustrating the preferred form of the invention Figure 1 is a front view of the exhibitor, some parts being removed; Figs. 2 to 7 inclusive are vertical cross sections, taken respectively from the lines A—A, B—B, C—C, D—D, E—E and F—F of Fig. 1; and Fig. 8 is a left-hand side view of Fig. 1 partly broken away.

In these views, the numeral 10 represents the right-hand side frame of the device, and 35 11 is an intermediate frame.

A driving-shaft 13, which may be driven either by an electric motor or from a car- 40 axle, is journaled in bearings 14, 15 carried by the frames 10, 11 on a substantially central line within the lower part of the device. This shaft has a gear-wheel 17, fixed thereon and meshing with a loose gear 18, mounted 45 on a shaft 19, directly above. The latter named shaft 19 is revolvably supported by bearings 20, 21, also carried by the frames 10, 11. The fixed gear 17 further engages with a pinion 22, secured to a shaft 23, jour- 50 naled in similar bearings 24, 25 of frames 10, 11, rearwardly and about midway between the driving-shaft 13 and the said shaft 19. Another pinion 26, also secured to the rear 55 shaft 23, engages a gear 28, similarly loosely mounted on said shaft 19. Due to the action of the intermediate shaft 23, the gears

18 and 28 are rotated in opposite directions. These two gears are provided on their adjacent sides with rims 29, 30 which face each other and have each a single ratchet-tooth 60 31, 32, the teeth on the respective rims being turned and designed to act in opposite directions, as more fully hereinafter described.

A hub 35, pinned centrally on the shaft 19 between the aforesaid rims 29, 30, is provided with a pair of arms 36, 37 carrying at their outer ends a short shaft 38, to the extremities of which are secured pawls 39, 40. The pawl 40 has an arm 41 that carries a pin 42, to which is anchored one end of a 65 spring 43. The other end of spring 43 is attached, as at 44, between the arms 36, 37. The tendency of said spring is to maintain either the pawl 39 or the pawl 40 in engagement with the corresponding ratchet-teeth, 70 31 or 32 as the case may be, when the arm 41 passes its neutral central position.

Adjacent to the bearing 20 on the shaft 19, is secured a pinion 47, which meshes with a gear-wheel 48, rotatable on a stud 49, which 80 latter is fixedly held in a boss 50 of the frame 10. A hub 51 connects the gear 48 to another pinion 52, engaged by a co-acting gear 55, which is fixed to a shaft 56, supported in journals 57, 58 on the frames 10, 85 11. A hub 59, having spaced arms 60, 61 is secured to the shaft 56, for instance by means of a pin, as shown. The ends of the arms 60, 61 are provided with flat springs 62, 63 one on each, which springs are disposed oppositely one to the other.

When, for example, the gear 18 drives the shaft 19, through the agency of pawl 40 in engagement with ratchet-tooth 32, the shaft 56 is rotated by the gears 47, 48, 52, 55, 95 thereby causing the arms 60, 61 to travel in a circular path with shaft 56, around to the opposite side, until the spring 63 strikes the pawl 39, bringing the latter into contact with the ratchet-tooth 31 and arm 36. The shaft 19 is then turned in the opposite direction, which also reverses the motion of the shaft 56, so that the arms 60, 61 return to the other side, in position to reverse the cycle again. The ratio of the change gears 100 47, 48 and 52, 55 predetermines the number of revolutions of shaft 19 in each direction before the reversing takes place.

On the left-hand side of the frame 11, is fastened to the shaft 19, an intermittent 110 gear 67, and co-acting therewith are two intermittent pinions 68, 69, disposed respec-

tively above and below the said shaft. Sprocket-wheels 70, 71 are held by screws, or other suitable means, to the said pinions 68, 69. Both the intermittent pinion 68 and 5 its sprocket-wheel 70 are rotatably carried on a stud 72, while the other intermittent pinion 69 and its sprocket-wheel 71 rotate on a stud 73. The studs 72, 73 are held in bosses 74 75 of the frame 11.

10 A sprocket-chain 76 runs from the sprocket-wheel 70 over intermediate sprocket-wheels 77, 78, secured respectively to shafts 79, 80 provided therefor. These shafts are journaled at one end in bearings 83, 84 on frame 15 11, and at the other end they are similarly journaled in an outboard side frame (not shown). Clamping-rolls, each composed of two parts, 85, 87 and 86, 88 respectively, are secured to the shafts 79, 80, one two part 20 roll to each shaft. The parts 85, 86 are fixed on their respective shafts, while the parts 87, 88 form caps that are held to 85, 86 by elastic ring clips 89, 90.

91 represents a curtain (omitted in Fig. 1) 25 of paper or cloth, having denoted thereon the reading or advertising matter to be exhibited. This curtain is clamped between the meeting edges of the parts 85, 87 and 86, 88 that compose the clamping-rolls and 30 which are suitably beveled to receive the ends of the curtain between them. As an extra precaution, to prevent slipping, the ends of the curtain may be pinned to the opposite beveled faces of the fixed parts 35 85 and 86, as indicated in Figs. 6 and 7. The curtain is wrapped so as to wind and unwind alternately from one clamping-roll to the other, and it is made to pass also over an idler roll 92, loosely mounted on a shaft 40 98, hereinafter referred to. From the sprocket-wheel 71 also runs a sprocket-chain 95, to and around another pair of sprockets 96, 97, secured respectively to shafts 98, 99 which are journaled at one end 45 in bearings 100, 101 on the frame 11. At the other end these shafts are supported in outboard bearings (not shown). A second curtain 102, similar to 91, is anchored at its ends to and within two-part rolls 105, 106, 50 constructed like the rolls 85, 87 and 86, 88 previously described. The curtain 102 also passes over an idler roll 107, mounted loosely on the shaft 79. The ends of the shafts for the said rolls are provided with coupling 55 members 108, so that any desirable number of curtain carrying rolls can be connected up in series, and thus be driven from one unitary actuating mechanism.

The curtains and rolls are inclosed in a 60 casing 109, the front half of which has an aperture or sight-opening 110, covered with some transparent material, permitting the matter inscribed, printed or depicted on the curtains to be readily viewed. This casing 65 may consist of a plurality of parts hinged

to one another, as at 111, and locked together, for instance, by means of a padlock or pin 112.

When the intermittent gear 67 is revolved in one direction by the shaft 19, the cogs 70 thereof are during a certain period of time in mesh with the intermittent pinion 68, causing the sprocket-wheel 70, through the chain 76, to drive the intermediate sprockets 77, 78, thereby rotating the shafts 79, 80 75 and thus unwinding the curtain 91 for instance from the roll 85—87 while it winds up on the roll 86, 88. Meanwhile the intermittent pinion 69 remains quiescent and the rolls 105, 106 are accordingly inactive, thus 80 keeping the curtain 102 during a corresponding period of repose in front of the opening 110. In the same manner the conditions of the rolls 85, 87, 86, 88 and 105, 106 are reversed, when the intermittent gear 67 85 engages the intermittent pinion 69, leaving the first mentioned rolls inactive. Thus, it is seen that one curtain always is traveling while the other curtain is at rest. When the direction of motion of the shaft 19 is 90 reversed in the manner hereinbefore described, the relative rotation of the rolls is obviously also reversed. This is timed to take place when the available length of curtain has been wound up on one set of rolls 95 and unwound from the other set.

Having described my invention what I desire to secure by Letters Patent and claim is:—

1. An exhibitor comprising a plurality of 100 curtains adapted for travel in opposite directions, rolls on and off which said curtains respectively wind and unwind, a driving shaft, a reversible shaft, loose gears revolved in opposite directions on said reversible 105 shaft from said driving shaft, ratchets moved by said loose gears, pawls secured to the reversible shaft alternately acted upon by said ratchets, a reverse controlling shaft geared with the reversible shaft, said controlling shaft having arms operating to throw said pawls successively into engagement with their respective ratchets and thereby drive the reversible shaft alternately in opposite directions, and mechanism intermittently and alternately connecting the reversible shaft with one or another set of said rolls whereby one curtain is moved while another is at rest. 115

2. In an exhibitor of the class described, 120 the combination of a driving shaft, a reversible shaft, a third shaft, oppositely rotatable gears actuated by the driving shaft and provided with engaging means, other means operating to rotate the reversible shaft alternately in opposite directions including a resiliently pressed connection having a plurality of operative positions between said reversible shaft and said engaging means, being adapted for alternate engagement with 125 130

the latter, shiftable means carried by the third shaft having a plurality of operative positions adapted for contacting with said resiliently pressed connection so as to change 5 its operative position and thereby reverse the direction of motion of said reversible shaft, a plurality of curtains adapted for travel successively in one direction and then in another, and operative connections transmitting 10 the motion intermittently from the reversible shaft to said curtains.

3. In an exhibitor, the combination of a driving shaft which may be rotated continuously in one direction, another shaft 15 capable of rotation in both directions, a pinion fixed on said driving shaft, gears loosely mounted on said other shaft, one of said gears being in mesh with said pinion and rotated thereby, intermediate shafting and 20 pinions operating to rotate another one of said loose gears in a direction opposite to said first loose gear, rims secured to the loose gears and having each a ratchet-tooth formed thereon, a hub on the reversible shaft 25 located between said rims, pawl-carrying arms on said hub, the pawls on said arms being adapted alternately to engage the ratchet-tooth on the rim of the corresponding loose gear, intermediate gears and shifting 30 means actuated by the reversible shaft and operating to control the direction of motion thereof first in one direction and then in the other, a plurality of curtains, rolls for said curtains, and intermittent 35 mechanism transmitting the motion from the reversible shaft to said rolls whereby the latter and curtains thereon are afforded consecutive periods of motion and rest.

4. In an exhibitor, the combination of a 40 driving shaft, a reversible shaft, loose gears revolved in opposite directions on said reversible shaft from said driving shaft, rims secured to said loose gears, having each a ratchet-tooth formed thereon, pawls carried 45 by the reversible shaft adapted for engagement with the ratchet-teeth on said rims, one of said pawls being provided with an arm, a spring anchored to said arm and capable of maintaining either pawl in engagement with the corresponding ratchet-tooth, change gears and shiftable means connected up with said reversible shaft and, 50 operating to control the direction of motion thereof alternately in opposite directions, a plurality of curtains, rolls therefor, and intermittent gears connecting the reversible 55 shaft with said rolls.

5. In an exhibitor, the combination of a driving shaft, a reversible shaft, loose gears 60 revolved in opposite directions on said reversible shaft from said driving shaft, a ratchet-tooth carried by each of said loose gears, an arm fixed to the reversible shaft between said loose gears, pawls carried by 65 said arm in position to engage alternately

each the ratchet-tooth on the adjacent loose gear, a third shaft, arms secured to said third shaft, springs on said arms revolved therewith so as to drive said pawls into alternate engagement with their respective 70 ratchet-teeth, change gears receiving their motion from said reversible shaft and transmitting it to said third shaft whereby the arms and springs thereof are directed against the pawls to control the movement 75 of either loose gear and corresponding motion of the arm on the reversible shaft, a plurality of curtains, rolls therefor, and intermittent mechanism operating to turn said rolls from the reversible shaft rotated in 80 either direction.

6. In an exhibitor, the combination of a plurality of curtains, sets of rolls therefor, an independent driving mechanism for each of said sets positively connected up with the 85 end rolls thereof arranged to wind one end and unwind the other end of said curtains, an intermittent mechanism common to said driving mechanisms for driving one curtain while the other is at rest, and a reversing 90 mechanism for said intermittent mechanism for causing the driving mechanism to travel first in one direction and then in the other whereby the sets of curtains are solely controlled by the rolls at both ends thereof to 95 move successively in alternate periods in opposite directions.

7. In an exhibitor, the combination of a plurality of curtains, rolls therefor, intermittent pinions connected with said rolls, an 100 intermittent gear adapted to mesh alternately with said pinions in such a manner that they will cause the curtains to move alternately step by step, one advancing while the other remains at rest and so on successively until their limit of travel is reached, and reversible operating means capable of turning said gear alternately in opposite directions, whereby the curtains are also reversed after reaching their said limit and 110 made to retrace their steps each in a correspondingly opposite direction.

8. In an exhibitor, the combination of a plurality of curtains adapted for travel first in one direction and then in another, a reversible operating mechanism intermediate gearing whereby each curtain is moved alternately and periodically, and means for positively holding both ends of the curtains 115 between periods of movement.

9. In an exhibitor, the combination of an operating shaft, means for rotating the same in reverse directions, a plurality of curtains adapted for travel in opposite directions, pairs of rolls on and off which said curtains 125 can wind and unwind, sprocket wheels connected with each pair of said rolls, intermittent pinions, other sprocket wheels connected up with said pinions, an intermediate intermittent gear intermeshing with said in- 130

intermittent pinions, and sprocket chains passing around said sprocket wheels, one chain being provided for the sprocket wheels on each pair of rolls and one intermittent pinion, whereby the pairs of rolls are rotated alternately step by step in opposite directions, one curtain traveling while the other is at rest, and the reverse.

10. In an exhibitor, the combination of a reversible actuating shaft, a plurality of curtains disposed side by side adapted for travel in opposite directions, a pair of driven rolls on and off which each curtain can alternately wind and unwind, an idler 15 for each curtain located in the plane of its rolls, a shaft common to the idler of one curtain and to one of the driven rolls of the adjacent curtain, said curtains having their said rolls and idlers reversely arranged, 20 sprocket wheels connected with said rolls, chains interconnecting said sprocket wheels, and means for giving said pairs of rolls and thereto connected sprockets alternate periods of movement and rest.

11. In an exhibitor, the combination of a plurality of curtains adapted for travel in opposite directions, rolls on and off which

each curtain can respectively wind and unwind, an idler roll for each curtain, sprocket wheels connected with the winding and unwinding rolls, chains interconnecting said sprocket-wheels, a reversible actuating shaft, and intermittent mechanism operating to move the rolls in sets alternately.

12. In an exhibitor, a plurality of curtains disposed side by side adapted for travel in opposite directions, a set of rolls for each curtain, two rolls in each set being located near one end of the curtain and the third at the other end thereof, said sets being reversely disposed, a reversible actuating shaft, and intermittent mechanism operating said rolls from said shaft, combined with a controlling shaft, and means connected with the latter, adapted to control 45 the direction of movement of said reversible shaft and curtains operated therefrom.

Signed at the borough of Manhattan in the county of New York and State of New York this 31st day of May A. D., 1912.
